APPARATUS FOR MELTING AND PROCESSING CRUDE OLEORESIN

Jesse O. Reed, Washington, D. C., assignor to Claude R. Wickard, as Secretary of Agriculture of the United States of America, and to his successors in office

Application March 27, 1941, Serial No. 385,508

3 Claims. (Cl. 210—150.5)

(Granted under the act of March 3, 1883, as amended April 30, 1928; 370 O. G. 757)

This application is made under the act of March 3, 1883, as amended by the act of April 30, 1928, and the invention herein described and claimed, if patented, may be manufactured and used by or for the Government of the United States of America for governmental purposes without the payment to me of any royalty thereon.

This invention relates to an apparatus for melting and processing crude oleoresin, or other resinous materials.

The object of my invention is to provide an apparatus for melting crude oleoresin, and preparing the same for filtration or purification in a process of refining crude oleoresin.

A further object of my invention is to provide an apparatus for the rapid and uniform melting of crude oleoresin, without foreign material, such as pieces of bark, leaves, chips, etc., coming in direct contact with the heating medium, in order that maximum yields are obtained both in quantity and quality of the end products.

Crude oleoresin usually contains a high percentage of foreign materials, such as pine chips, bark, leaves, sand, etc. The components and physical properties of oleoresin vary throughout the operating season, and range from a highly viscous material, containing some crystalline substances, to a dry mass known as "scrape." Large quantities of scrape are often mixed with the viscous oleoresin to form a material which is difficult to melt uniformly, because of the high temperature required to melt the "scrape," as compared to the viscous fluid portion of the oleoresin. Because of variable physical properties of the crude products to be handled, and because of the ease with which undesired color is added to the material being processed, by the improper application of heat, especially to the color-adding foreign substances, such as bark, chips, leaves, etc., my apparatus has been designed so that a uniformly melted and undamaged product, having a relatively low viscosity, can be prepared without difficulty. Subsequent steps in an oleoresin refining process, therefore, can be simplified and adapted to function more satisfactorily.

The accompanying drawing illustrates in a preferred form the apparatus embodying the principles of my invention.

Figure 1 is a vertical sectional view of my oleoresin melting apparatus.

Figure 2 is a fragmentary sectional view of the base of my apparatus showing another preferred

design for carrying out the principles of my invention.

Similar numerals refer to similar parts throughout the views.

Referring to the drawing, and more particularly to Figure 1, the apparatus consists essentially of an elongated cylindrical pressure tank 1, having an upper reduced neck 2, provided with a removable head 3, through which the tank is charged with the material, such as crude oleoresin, to be melted. Head 3 is adapted to be clamped in place by means of swinging bolts 4 carried by projecting ears 5 secured to said neck 2 by any suitable means. Openings 6 and 7 are provided in head 3 for safety and vent valves, not shown.

The lower end of tank 1 is provided with a reduced cylinder portion or sump 10, which extends through and is joined to the dished bottom 11 of the tank and outer wall of steam jacket 12. Reduced cylinder portion or sump 10 is provided with: outlet pipe connection 9 for discharge of contents of tank 1; steam pipe connection 14 for introduction of live steam to the interior of the tank, and turpentine or solvent pipe connection 15 for introduction of solvents or diluents into the tank. Lower chamber or sump 10, fitted with bottom 13, serves as a converging central point for the collection and distribution of materials either to be introduced or removed from the tank.

In the lower portion of pressure tank 1 there is positioned a perforated flat bottom basket 17, removably supported in spaced relation to the walls of the tank by an upper annular baffle 18 secured to the inner cylindrical wall of the tank, and having a cylindrical flange 16 engaging said basket. In order to facilitate the removal of basket 17, ears 19 that project from upper bands of the basket are provided for the insertion of hooks from a hoisting apparatus, not shown.

Basket 17 may be formed of woven wire mesh cloth 35, preferably of wire size .080 inch diameter and mesh size No. 5. Basket 17 is of generally cylindrical shape with the wire mesh bottom reinforced and backed with a reinforcing perforated plate 20 of a gauge of sufficient thickness and stiffness to maintain the original shape of basket 17 when filled completely. Reinforcing perforated plate 20 of the bottom of basket 17 rests upon supports 8 welded to bottom 11 of tank 1, said supports 8 only lifting said bottom of basket 17 a sufficient space from tank bottom 11 to permit drainage of material into sump 10.

It is essential that the bottom of basket 17 be so positioned that it rest upon, or be raised only sufficiently from bottom 11 to permit drainage from the space outside of basket 17. It is also essential that this close proximity be maintained so that the material difficult to melt such as "scrape" and crystalline oleoresin that may have settled to the bottom of basket 17 not only comes near the source of heat from jacket 12, but also is subjected to the action of live steam or added turpentine, introduced either in sump 10, or through pipe 36, hereinafter described. The restricted clearance between the bottom of basket 17 and bottom 11 of tank 1 causes the live steam and/or turpentine from sump 10 or pipe 36 to be forced into, through, and within basket 17, thereby bringing direct heat from the live steam and dissolving action of turpentine into intimate contact with the scrape, sediment, residue, etc., within basket 17.

A heating coil 21 is placed in the space between the inner side walls of tank 1 and basket 17, said coil 21 receiving steam, or any heating medium, at connection 22 and exhausting at connection 23. Steam, or any other heating medium, is supplied to jacketed bottom 11 through pipe connection 24 in jacket 12 and exhausts from pipe connection 25 located near lower chamber 10.

Pipe 26 extends from and through baffle 18 toward neck 2 and serves as vent or pressure equalizer between the exterior and interior of basket 17 and also provides means for transfer of products between the spaces outside and inside of basket 17.

Pipe connection 27, controlled by valve 41, is provided for exhausting vapors from tank 1, said pipe connection 27 running to a condenser, not shown, for recovery of said vapors. Pipe connection 28 is adapted for the introduction of steam into the upper chamber of tank 1. Pipe connections 29 and 30 are auxiliary openings for the insertion of a thermometer and pressure gauge, not shown. Openings 31, 32 and 33 are adapted for insertion of valves, not shown, to determine liquid level within tank 1, as well as points which can be used for the introduction of solvents or live steam.

Since the size, especially the diameter of tank 1, influences: (1) the relationship of heating coil 21 to material to be melted, especially that disposed in the center of basket 17; and (2) the means for distribution of solvents, steam, etc., introduced in sump 10 for melting and liquefying materials retained within basket 17, changes or modifications in said basket 17 become necessary for the satisfactory performance of a large diameter tank. Such modifications as are necessary are illustrated in Figure 2. Perforated tube 34 extends through the center of basket 17 with top closed by means of cover 39 and having its bottom open. The bottom of tube 34 projects through reinforcing perforated plate 20 and wire mesh 35 forming the bottom of basket 17. Perforated tube 34 is covered with wire mesh 35. Perforated tube 34 is braced in place by brackets 40 extending from cover 39 to flanged top 16 of basket 17. Running through bottom 13 of sump 10 is pipe 36, which extends up and inside of perforated tube 34, of approximately one-third its length. Valves 37 and 38 control the rates of flow of solvent and steam to be introduced into tank 1 through pipe 36 in close proximity of material to be melted or dissolved adjacent to wire mesh 35 on perforated tube 34. Pipe 36 can be

either open or closed at the top with perforations in its side.

In operation, head 3 is first removed; all outside pipe connections closed, and the tank charged with the material to be melted, such as crude oleoresin. The tank is filled to a level just below pipe connection 27, thereby filling basket 17, resting in place in the bottom chamber of tank 1. Removable head 3 is then fastened in place, 10 vapor tight, by means of swinging bolts 4. Steam is admitted into coil 21 and into steam jacket 12 of tank bottom 11 through their respective inlets 22 and 24. As the oleoresin becomes heated by the steam, some of the material within basket 17 melts and passes through wire mesh cloth 35 and drains into the bottom of the tank and into sump 10. The refuse and unmelted material is retained in basket 17 by wire mesh cloth 35. As melting continues, the chamber between the bottom and side of basket 17, baffle 18, and the sides of the tank become filled. The melted gum within this said chamber in coming in contact with coil 21 and steam jacketed bottom 11 rapidly reaches a distillation temperature which, in giving off turpentine and steam vapors, permeates the mass within and above basket 17. At distillation temperature some of the crude oleoresin rapidly melts, while the heavier particles descend to the bottom of basket 17. Continued 20 heating and melting of the oleoresin will in time produce a vapor pressure within the tank, so valve 41 is preferably kept open, permitting the products of distillation to be vented and recovered in a condensing apparatus, not shown. Distillation at atmospheric pressure causes a greater amount of turbulence than is possible if the heating is done under pressure. The result is a more rapid rate of melting. It is to be noted that this heating is done so that the foreign matter previously referred to does not come in contact with steam coil 21 or jacketed bottom 11 of the tank.

With many classes of crude oleoresin no other source of heat is required other than that supplied indirectly through pipe coil 21 and jacketed bottom 11. Live steam can be applied directly to the oleoresin, but investigations have shown that the introduction of live steam to crude oleoresin has a tendency to leach from the foreign material present in the crude oleoresin water soluble and color-adding materials, which must be removed in a gum refining process, if maximum yields are to be obtained. Therefore, live steam is used and introduced into tank 1, either through connection 14, or control valve 37, only when agitation and a more direct application of heat is required to melt "scrape" and crystalline oleoresin that may have settled to the bottom of basket 17.

When live steam is required for the melting of certain classes of oleoresin, it is introduced in sump 10, where it distills or causes a turbulence of melted gum around the base and side of basket 17, resulting in the melting of the oleoresinous material within said basket. The same principle of melting is also employed in the modification as shown in Figure 2. Live steam is admitted through control valve 37, into pipe 36, and exhausts inside of perforated tube 34. In this case also distillation or turbulence of melted gum occurs within a close proximity of possibly some of the unmelted products settled within basket 17. A melting of all the products is accomplished without the excessive use of live steam; without an excessive amount of distillation and isomerization resulting in the formation of a resinous-like

mass, difficult to filter and handle through the pipe lines of turpentine gum refining processing equipment.

The apparatus of my invention is not only adapted to melt crude oleoresin, but it is equipped to prepare the same for treatment in refining processes. In processes where turpentine is added to the crude oleoresin as a diluent my apparatus is adapted to use turpentine instead of live steam as a means of obtaining a thorough and satisfactory melting of all the oleoresinous materials and a complete separation and recovery of the oleoresin from the refuse remaining in the basket after the removal of the melted products. Satisfactory operation is obtained because it is possible to introduce the turpentine as a diluent within close proximity of the materials difficult to melt, and the refuse, which have settled in the bottom of basket 17. Turpentine is introduced in sump 10 through pipe connection 15, or control valve 38. In Figure 2, turpentine enters through control valve 38, pipes 15 and 36, and into tube 34, where it is extruded into the material in basket 17. The melting action that takes place is similar to that previously described when steam is being introduced. In a like manner, a clean separation and complete recovery of the oleoresin from the refuse withheld in the bottom of basket 17 is obtained.

My apparatus also provides for the introduction of live steam with the turpentine being added as a diluent. A combination of live steam and turpentine accelerates the rate of melting, because of the added heat from the live steam. Steam is introduced into sump 10 through valve 37 and turpentine through valve 38, as shown in Figure 2.

Preliminary to discharging tank 1, valve 41 is closed. A pressure is thereby produced in the tank, which is equalized on both sides of basket 17 by pipe 26. Valve 42, controlling the exhaust from sump 10, is then opened and the melted contents of the tank are forced to a filter, or any other desired equipment of an oleoresin refining process. Additional pressure, if required, can be obtained by the admission of live steam into the top of tank 1 by means of pipe connection 28.

After tank 1 is discharged, the recovery of the oleoresin remaining in the refuse withheld in basket 17 can be accomplished by the introduction of additional turpentine, as previously stated, or by the introduction of live steam through any of the connections provided in the tank, so as to obtain a steam pressure or temperature which will permeate the mass of refuse and melt therefrom the oleoresinous materials.

It will be seen that the apparatus which I have provided is adapted for the processing of oleoresin in addition to melting; that the melting of crude oleoresin without the necessity of the use of quantities of live steam is made possible, and that crude oleoresin of all classes can

be processed so that a product having satisfactory filtration characteristics is made available for subsequent steps in an oleoresin refining process.

Having thus described my invention, what I claim for Letters Patent is:

1. A melting tank comprising a chamber having a vertical cylindrical housing and a dished bottom, a sump chamber below and communicating with said dished bottom, a foraminous basket vertically disposed above said sump chamber in the lower part of said housing, said basket having an upper rim, brackets to support said basket in spaced relation above said dished bottom, an annular baffle extending downwardly from said housing to said upper rim, heating means in said housing surrounding said basket, a foraminous tube axially disposed in said basket, bracing members extending from the upper end of said tube to said rim, and a pipe extending from the exterior of the sump chamber through the bottom of and into said tube.
2. A melting tank comprising a chamber having a vertical cylindrical housing and a dished bottom, a sump chamber below and communicating with said dished bottom, a foraminous basket vertically disposed above said sump chamber in the lower part of said housing, said basket having an upper rim, brackets to support said basket in spaced relation above said dished bottom, an annular baffle extending downwardly from said housing to said upper rim, a tube in the upper part of the housing having one end through the baffle to communicate with the space below said baffle and the other end in the form of an inverted U at a point near the top of the housing, and heating means in said housing surrounding said basket.
3. A melting tank comprising a chamber having a vertical cylindrical housing and a dished bottom, a sump chamber below and communicating with said dished bottom, exterior pipes communicating with said sump chamber, a foraminous basket vertically disposed above said sump chamber in the lower part of said housing, said basket having an upper rim, brackets to support said basket in spaced relation above said dished bottom, an annular baffle extending downwardly from said housing to said upper rim, a tube in the upper part of the housing having one end through the baffle to communicate with the space below said baffle and the other end in the form of an inverted U at a point near the top of the housing, a foraminous tube axially disposed in said basket, the upper end of said tube being closed, wire mesh surrounding said tube, bracing members extending from the upper end of said tube to said rim, a pipe extending from the exterior of the sump chamber through the bottom of said tube a substantial distance thereabove, and heating means in said housing surrounding said basket.

JESSE O. REED.
